UNITED STATES PATENT OFFICE.

VERNON BEAUFORD CARR AND SAMUEL HERBERT BROSHAR, OF LEBANON, INDIANA.

AUTOMATIC DRAFT REGULATOR.

Application filed December 8, 1921. Serial No. 520,977.

To all whom it may concern:

Be it known that we, VERNON B. CARR and SAMUEL H. BROSHAR, both citizens of the United States, and residents of Lebanon, in the county of Boone and State of Indiana, have invented a new and useful Improvement in Automatic Draft Regulators, of which the following is a full, clear, and exact description.

10 Our invention relates to improvements in automatic draft regulators for furnaces or the like, and it consists in the combinations, constructions and arrangements herein described and claimed.

15 An object of our invention is to provide an automatic draft regulator for a furnace which is actuated by the steam pressure in the boiler.

20 A further object of our invention is to provide a device of the character described which has adjustable means for automatically keeping the pressure of steam in the boiler at a predetermined point.

25 A further object of our invention is to provide a device of the type described, which automatically regulates the opening and closing of the draft door and also the opening and closing of the check draft.

30 A further object of our invention is to provide a device of the type described, which is relatively simple in construction and which is not likely to easily get out of order.

35 Other objects and advantages will appear in the following specification, and the novel features of the invention will be particularly pointed out in the appended claim.

Our invention is illustrated in the accompanying drawings, forming part of this application, in which—

40 Figure 1 is a front elevation of the device as shown applied to a furnace, parts of the device being shown in section, and

Fig. 2 is a sectional view of the device.

In carrying out our invention, we make use 45 of a furnace 1, of ordinary construction, which has a pipe 2 integral with the top thereof. We then provide a casing 3 which has a boss 4 at the lower end thereof and through which the pipe 5 is disposed. The

50 pipe 5 is adapted to extend a short distance into the pipe 2 and thus securely holds the casing 3 to the furnace 1. The casing 3 is divided into two compartments 6 and 7 by means of a centrally disposed partition 8.

55 The partition 8 extends within a spaced distance from the bottom 9 of the casing 3, thus

providing an opening 10 between the compartment 6 and the compartment 7. Slidably disposed in the compartment 7 is a float 11, the float being provided with a vertical bifurcated rod 12 which is adapted to extend through an opening 13 in the top 14 of the casing 3. The casing 3 is further provided with an inlet 15 through which water is adapted to be poured for a purpose which will be herein-after described. It will be apparent that any variation in the level of the water in the chamber 7 will raise or lower the float 11.

70 The furnace 1 is provided with the usual draft regulator 16 and a check draft 17. The draft 16 and check draft 17 are connected to each other by means of a cable 18 which is disposed over two pulleys 19, the latter being secured to a transverse beam 20. A bar or lever 21 is pivotally mounted on a support 22 and has one of its ends connected to the cable 18. The casing 3 carries two guide members 23 in which the bar 21 is slidably disposed. The bar 21 is also disposed in the slot of the rod 12 and is secured thereto by means of a pin 24. It will now be obvious that any movement of the float 11 will actuate the doors 16 and 17. Counterbalance weights 25 are slidably disposed on the lever 21. The chamber 7 is further provided with a graduated water tube 26 and is also provided with an air valve 27.

75 From the foregoing description of the various parts of the device, the operation thereof may be readily understood. It will be obvious that any variation of the length of the pipe 5 which extends into the chamber 6 will also vary the level of the water in the chamber. The pipe 5 is in direct communication with the steam boiler 27' of the furnace 1. Assume now that the steam is being generated in the boiler 27'. The steam will rise in the pipe 5 and will pass into the upper portion of the chamber 6 and will force the level of the water in the chamber 6 downwardly. The water from the chamber 6 will pass through the opening 10 and into the chamber 7, thus raising the float 11, which in turn will swing the lever 21 so as to close the door 16 and to open the door 17. It will be observed therefore that a less quantity of air will be admitted into the 80 furnace 1 and that a greater quantity of air will be admitted into the smoke pipe 28.

This will cause the fire in the furnace to die down. The steam pressure in the boiler 27' and the chamber 6 will therefore be lowered and the levels of the water in the chambers 6 and 7 will resume their normal positions, thus lowering the float 11. The lever 21 will then be swung back to normal position and will open the door 16 and close the door 17.

- 10 It will be apparent that this device is automatic in operation and will effectually keep the steam pressure in the boiler 27' at a predetermined point. It will further be observed that the raising or lowering of 15 the pipe 5 with respect to the chamber 6 will vary the length of the stroke of the float 11 in the chamber 7. In some types of furnaces, the doors 16 and 17 have to be swung through a greater arc than the doors of 20 other types of furnaces. By merely changing the position of the pipe 5 in the chamber 6, we can readily determine the length of the movement of the float 11, which in turn, regulates the movement of the doors 16 and 25 17. The rod 12 is provided with a plurality of openings 29 therein, through which the pin 24 can be disposed. This construction provides a fine adjustment between the float 11 and the cable 18. The graduated water 30 tube 26 shows at any time what steam pressure there is in the boiler 27', since the variation of the steam pressure in the boiler 27

will raise or lower the level of the water in the tube 26. In the present instance we have graduated the pipe to show a variation 35 of steam pressure in ounces.

As heretofore stated, we have provided a device which is simple in construction, is automatic in operation, and which has few 40 moving parts.

We claim:

The combination with a furnace having a boiler, a draft door and a check door, of a casing having two compartments therein in communication with each other at their lower ends and having a fluid therein, a pipe connecting said boiler with one of said compartments, a float in the other compartment, and means operatively connecting said draft and check doors to said float, said means comprising a bifurcated rod supported on said float, said rod having a plurality of spaced apart holes extending transversely therethrough, a lever pivotally mounted intermediate its length on said casing and having an opening therethrough, a pin arranged to be received in the opening of said lever and in one of the openings in said rod, and cables connected at one end with said lever and with said check and 50 draft doors respectively.

VERNON BEAUFORD CARR.
SAMUEL HERBERT BROSHAR.
